UNITED STATES PATENT OFFICE

118,711

DESIGN FOR A COMBINATION MAIL BOX AND HOUSE NUMBER PLATE

Nina L. Poole, Riverside, Calif.

Application March 23, 1939, Serial No. 84,056

Term of patent 3½ years

To all whom it may concern:

Be it known that I, Nina L. Poole, a citizen of the United States and a resident of Riverside, county of Riverside and State of California, have invented a new, original, and ornamental Design for a Combination Mail Box and House Number Plate, of which the following is a specification, reference being had to the accompanying drawings, forming part thereof.

In the drawings: Figure 1 is a front elevation; Figure 2 is a side elevation; and Figure 3 is a top view of a combination mail box and house number plate, showing my new design.

I claim:

The ornamental design for a combination mail box and house number plate, as shown.

NINA L. POOLE.
